UNITED STATES PATENT OFFICE.

EDGAR F. HATHAWAY, OF BOSTON, MASSACHUSETTS, ASSIGNOR TO AMERICAN WARP DRAWING MACHINE COMPANY, A CORPORATION OF MAINE.

WIRE-COILING MACHINE.

1,207,911.

Specification of Letters Patent. Patented Dec. 12, 1916.

Application filed October 5, 1906, Serial No. 337,575. Renewed June 16, 1916. Serial No. 104,120.

To all whom it may concern:

Be it known that I, EDGAR F. HATHAWAY, a citizen of the United States, and a resident of Boston, in the county of Suffolk and 5 State of Massachusetts, have invented an Improvement in Wire-Coiling Machines, of which the following description, in connection with the accompanying drawings, is a specification, like characters on the drawings 10 representing like parts.

This invention relates to wire coiling machines, the product whereof may be used for a large variety of purposes, but is particularly intended for use as a normally contracted extensible member employed in connection with the harnesses of looms to engage the heddles thereof individually and regularly space them and in coöperation with other elements of a warp drawing-in 15 machine to assist in spreading the heddle eyes to facilitate the drawing-in operation.

In the accompanying drawings, wherein merely one type or embodiment of the invention is illustrated, in order that the principles of operation thereof may be made clear, Figure 1 represents a side elevation of one form of wire coiling apparatus embodying my invention, many of the herein shown horizontally disposed parts being broken 20 away mid length for convenience of illustration; Fig. 2 is an end elevation of the mechanism shown in Fig. 1, looking from the left in said figure; Fig. 3 is a longitudinal vertical section of one form of carriage 25 mounted for relatively axial movement with respect to the mandrel whereon the wire is coiled; Fig. 4 is an end elevation of the said carriage looking from the right in Fig. 3; Fig. 5 is a rear elevation of the said carriage, showing the point at which the wire 30 is delivered thereto; Fig. 6 is an enlarged longitudinal sectional view of the abutment and abutment coöoperative member, which, in the present type of the invention, co-act 35 with the mandrel in the coiling of the wire, the curvature of the adjacent ends which I sometimes resort to, being greatly exaggerated for purposes of description and illustration; Fig. 7 is an enlarged detail in side 40 elevation of a portion of the left-hand end of the machine shown in Fig. 1, viewing said figure; Fig. 8 is an end elevation of a form of clutch herein employed for imparting rotation to the mandrel; Fig. 9 is a de-

tail in plan showing a portion of a terminal 55 supporting bar having an adjustable contact member thereon, whereby the machine is suitably stopped; Fig. 10 represents in end and side elevation the adjustable contact member of the terminal supporting bar; 60 Fig. 11 represents a form of clutch preferably employed to prevent opposite rotation of the mandrel when the bar is thrown off the machine; and, Fig. 12 illustrates diagrammatically a system of wiring employed 65 to electrically control the stopping of the machine.

Having now reference to that single type or embodiment of the invention herein chosen for illustration and referring more 70 particularly to Figs. 1 and 2, the operative parts of the machine are supported upon end uprights or standards, 1, 1, having suitably disposed thereon at proper distances apart horizontal bearings, 2, wherein are 75 suitably supported horizontal connecting bars or rods, 3. Supported for rotation in suitable bearings, 4, 4, in said uprights, 1, 1, are arranged one or any desired number of rotatable mandrels, 5, two being herein 80 shown. It is apparent that the mandrels need not be arranged in a vertical series, as shown, but that their arrangement may be largely varied, as desired. If desired, one end of said mandrel or mandrels, and as 85 herein shown the right-hand end (Fig. 1) may be received within enlarged bearings, 4, provided with removable bearing nuts, 6, whereby the mandrels may be steadied in their rotative movement, which may be im- 90 parted to them in any desired manner. Herein I have shown each of them as provided with clutch members, 7, splined thereon and supported for longitudinal move- 95 ment with respect to the opposing and pref- erably band driven clutch members, 8, through the medium of a clutch operating carriage composed of vertical end bars, 9 and 10, the latter preferably having seg- mental bearings frictionally impinging 100 against the adjacent, horizontal rods, 3, for sliding movement thereon, said bars, 9 and 10, being herein shown as connected by hor- 105 zontally arranged rods, 11. Any suitable form of clutch may be employed, but herein I have shown in Figs. 7 and 8, a preferred or convenient type provided with relatively movable interengaging conical members

each provided with a pin, 12, concentrically arranged with respect to the center of rotation of the clutch members and adapted to overlap when said members are engaged, 5 thereby to impart motion to the clutch member, 7, to rotate the mandrel or mandrels, 5. In order to prevent reverse rotation of the mandrel when its driving clutch is disengaged, I preferably employ means to prevent reverse rotation thereof and have herein shown (Figs. 1 and 11) clutches, 13, comprising in this instance a ball and ratchet clutch of any preferred construction.

In the present type of the invention the 15 wire to be coiled is delivered to the mandrel and one end thereof is attached thereto, so that in the rotation of the mandrel the wire is coiled thereon and preferably against a suitable abutment disposed in wire coiling 20 relation to said mandrel and adapted for relative axial movement with respect thereto, in order that the wire may be progressively coiled. In the present type of the invention axial movement is imparted to the so-called 25 abutment, herein shown (Figs. 3 and 6) as a sleeve, 14, mounted for sliding movement upon the mandrel and preferably clamped in a suitable carriage, 15, which, during the coiling of the wire, is in this type of the invention fed or moved axially of the corresponding mandrel by the wire as coiled, such method of carriage movement being in this instance preferred to a carriage feeding means, which might, however, be employed 30 in certain cases where desired. It is apparent that the relative axial movement of the carriage and mandrel may in suitable cases be secured by axial movement of the latter. The carriage herein shown is preferably positioned between adjacent horizontal bars, 3, and to that end is shown as provided with segmental or, if preferred, encircling bearings at the top and bottom thereof, which preferably so closely engage the said bars 35 as to secure sufficient friction to oppose the feeding movement imparted by the coiling wire.

If no carriage feeding means be employed and the coiling of the wire itself be relied 40 upon to move the carriage axially of its mandrel, and if said carriage be provided with frictional or other means to oppose the carriage onward forcing movement of the coiling wire, supplemental means may be provided to oppose such onward movement and as a convenient type thereof, there are 45 herein shown (Fig. 1) weights, 16, which may be varied as desired, and are suitably connected by bands or other flexible members, 17, herein shown as guided over loose pulleys, 18, mounted upon a bracket, 19, said bands being adapted to be connected to the respective carriages, but herein shown as detached therefrom.

65 In the present type of the invention wire

for each carriage is carried (Fig. 2) upon spools, 19, suitably mounted in upright standards, 20, preferably at the rear of the carriages, and is delivered to the carriages in any suitable manner, but as herein shown 70 (Fig. 5) through an opening, 21, suitably provided in a preferably detachable plate, 22, the wire then passing to the corresponding mandrel, 5, to which one end thereof is preferably attached, so that in the rotation 75 of the mandrel the wire is wound thereabout in a coil or helix the spires or turns of which are preferably in contact with each other, but may be more or less separated, according to the rate of relative axial movement of the 80 carriage, which may be varied as desired by opposing less friction to the said relative movement of the carriage or in any other preferred manner.

Viewing Fig. 3, it will be apparent that 85 the wire, as delivered to the rotating mandrel, is, in the present embodiment of the invention, coiled thereabout and against the end of the abutment, 14, which, being herein shown as mounted upon the carriage, 15, is, 90 by the coiling of the wire, gradually moved axially of the mandrel, each newly positioned spire or turn of the helix or coil being laid between the end, 23, of the abutment, 14, and the forward end of the coil. 95

In the present type of the invention I prefer to employ in conjunction with the abutment, 14, a so-called abutment coöperative member, 24, herein shown as disposed co-axially with the abutment, 14, and adjacent 100 the same, so that the wire is delivered to the mandrel between the said abutment and abutment coöperative member. It will be observed (Fig. 3) that herein said abutment coöperative member is shown as having an axial opening of a diameter exceeding that of the abutment, 14, and preferably by the diameter of the wire or the enlarged dimension of the wire in cross section, if a wire having an enlarged dimension in cross section be employed, whereby in the onward movement of the carriage the said abutment coöperative member moves over the coiled wire, which, at the beginning of the operation, is preferably threaded through the 110 axial opening in the abutment coöperative member to the point where it is fastened to the mandrel.

When an abutment coöperative member is employed the same may be fixedly positioned with regard to the abutment; but inasmuch as any given quantity of wire is apt to vary somewhat in diameter throughout its extent, I preferably mount the abutment coöperative member with capacity for 120 axial yielding movement, although it is apparent that such movement being relative to that of the abutment, 14, may be secured by rendering either the abutment or abutment coöperative member axially yielding. 130

Although said yielding movement may be secured in many different ways, I have herein shown the said abutment coöperative member, 24, as having such capacity and to that end (Fig. 3) have mounted the same for sliding movement in a boss, 25, of the carriage and provided limiting means to oppose its movement in a direction away from the abutment, 14, such means herein comprising a vertically disposed plate, 26, having an open ended slot, 27, therein, through which the mandrel passes, said slot being of less diameter than the outer dimension of the abutment coöperative member, 24, thereby presenting a stop to the axial yielding movement of the latter. I preferably so mount the plate, 26, that the position thereof may be adjusted axially of the mandrel and for that purpose have in this type of the invention, provided a horizontal headed pin, 28, suitably mounted in an axial opening, 29, in the carriage and preferably guided therein by the reduced end of a screw, 30, engaging an elongated socket in said pin, the opposite end whereof being herein shown as having a nut, 31, threaded thereon, between which and a shoulder of the carriage is provided a coil spring, 32, the tension of which may be adjusted by the nut, 31. The said spring tends normally to force to the left, viewing Fig. 3, the plate, 26, which is herein shown as having a slot, 33, near the upper end thereof for the passage of said pin, the said plate being thus yieldingly positioned between the headed end of the pin and the carriage, and pivotally mounted at its opposite end upon a pin, 34, axially disposed with respect to the mandrel and preferably having a screw threaded adjustment, 35, in the carriage, whereby the plate may be vertically alined, a coil spring, 36, being herein shown as encircling said pin between the plate, 26, and a shoulder formed in the carriage, the member 24 thus being removable without disturbing the adjustment of the coiled spring 32.

It is apparent that wire of any chosen diameter and any desired cross section may be coiled in the manner previously described, but I sometimes prefer to employ a wire having an enlarged dimension in cross section and sometimes to dispose such enlarged cross section at right angles to the axis of the coil or the mandrel. In such cases the wire may be delivered as desired and irrespective of the disposition of the enlarged cross dimension or section thereof to the opening, 21, and is received between the adjacent ends of the abutment, 14, and abutment coöperative member, 24, in cases where the latter is employed, by which the wire, however received thereby, may be so positioned and if necessary, partially turned or rotated, that the enlarged dimen-

sion thereof in cross section is disposed as described at right angles to the axis of the coil.

I have discovered that the spires or turns of the coil or helix have a tendency as coiled, 70 to assume a position in which the opposing faces of the spires are not truly normal to the axis of the coil, but slightly inclined thereto in one direction or the other. To counteract this tendency I may and preferably do employ what I herein term a spire truing device. To that end, in the present type of the invention I preferably slightly concave the wire receiving end of the abutment, 14, this construction being shown very 80 much exaggerated in Figs. 3 and 6 for purposes of illustration. I prefer to render the adjacent end of the abutment coöperative member, 24, correspondingly convex, if such member be employed, and have herein shown the same to an exaggerated degree.

The face of the abutment is substantially normal to the axis of the mandrel, although, as described, I preferably provide spire truing means effected, in this embodiment of my invention, by rendering the adjacent ends of the abutment and abutment coöperative member respectively concave and convex and preferably very slightly so. 90 According to the disclosed embodiment of the invention, I provide an abutment coöperative member, the faces whereof are curved with respect to a plane cutting the mandrel at right angles to the axis of said 100 mandrel. Said faces may furthermore be defined as eccentric to said cutting plane, and also as deflected preferably slightly from parallelism with the spires of the completed wire.

I prefer to employ means for automatically stopping each mandrel upon the completion of the coil formed thereon and preferably employ means whereby the rotation of each mandrel may be stopped independently of that of the others, if a plurality be used. As illustrating one embodiment of means for accomplishing this result, I have herein provided (Figs. 1, 9 and 12) one or more horizontally disposed terminal supporting bars, 37, preferably mounted in the end standards, 1, and suitably insulated therefrom, the number of terminal supporting bars employed corresponding to the number of mandrels and each bar having 110 preferably mounted thereon for longitudinal adjustment (Fig. 10) a terminal or contact member, 38, herein shown as consisting of a sleeve, 39, having a set screw, 40, to secure the same in its adjusted position and a detachable contact plate, 41, forming (Fig. 12) a terminal of an electric circuit, the other terminal thereof being furnished by the carriage and preferably (Fig. 4) by a pin or wire, 42, laterally extending therefrom to 120 130

contact with the said plate, 41, when the required length of wire has been coiled about the mandrel, said carriage being grounded through the machine. Within the said electric circuit is provided (Figs. 1, 7 and 12) a number of electromagnets, preferably corresponding in number to the mandrels employed and adapted to move when energized, corresponding armatures, 44, herein shown 10 as having shouldered portions to engage a portion of the clutch operating carriage, and, as herein shown, the bar, 9, thereof, and acting when in the position shown in Figs. 1 and 7, to oppose outward movement 15 of the carriage or movement to the left, viewing said figures.

While I may employ various devices tending to move the clutch carriage or carriages outwardly, or to the left, viewing Fig. 1, 20 thereby to stop the rotation of the mandrel or mandrels, I preferably and herein have provided operative connections between the said clutch or clutches or the carriages therefor and (Fig. 2) braking means, 45, for 25 the wire delivery spools, which, in the present embodiment of the invention are designed to be applied to the respective wire delivery spools upon the stoppage of the respective mandrels. Each braking member, 30 45, in the present type of the invention, tends through gravity to assume its braking position as illustrated in Fig. 2, but is normally and during the operation of the machine held elevated from its spool 35 through connections with the driving clutch of the respective mandrel, such connection in the present instance comprising (Fig. 2) upstanding arms, 46, secured upon horizontally disposed bars, 47, of the braking 40 means, which are mounted in the standards, 20, and connected through the links, 48, with bell crank levers, 49, suitably sleeved upon a vertical rod, 50, herein shown as supported from one of the end standards 1, 45 the opposite arm 51 of each bell crank being pinned to a horizontal rod, 11, of the corresponding clutch carriage. Since the outward or disengaging movement of each clutch carriage is opposed by the corresponding armature, 44, when its magnet is unenergized, the corresponding braking member, 45, is in the present embodiment of the invention through the described or other suitable connection, held elevated. Immediately, 50 however, upon the movement of either armature, the clutch carriage is released and the weight of the braking means moves the said carriage into clutch disengaging position. If desired, and as herein shown, each armature 55 is provided with a finger piece, 52, whereby the operative may withdraw the armature and stop the rotation of the mandrel whenever desired.

Having thus described one type or embodiment of the invention, it will be under-

stood that although I have employed specific terms in describing the same, such terms are used in their descriptive sense only and not for purposes of limitation, and that the scope of the invention is defined in the following claims.

Claims:

1. A wire coiling machine comprising a rotatable mandrel, an abutment mounted thereon for relatively axial movement and having an operative face substantially normal to the axis of the mandrel and wire delivery means to deliver a wire to said mandrel to be coiled thereon against said abutment. 75

2. A wire coiling machine comprising a rotatable mandrel, an abutment mounted thereon and axially movable with respect thereto, and wire delivery means to deliver a wire to said mandrel in a direction substantially normal to the axis of the mandrel to be coiled thereon against said abutment. 80

3. A wire coiling machine comprising a rotatable mandrel, an abutment mounted thereon for axial movement, and having a spire forming face with which the wire engages as it is coiled, restraining means to oppose the movement of said abutment, and wire delivery means to deliver a wire to said mandrel to be coiled thereon against said abutment. 90

4. A wire coiling machine comprising a rotatable mandrel, an abutment mounted thereon for axial movement, and having a spine forming face substantially normal to the axis of the mandrel, friction restraining means to oppose the said movement of the abutment, and wire delivery means to deliver a wire to said mandrel to be coiled thereon against said abutment. 100

5. A wire coiling machine comprising a rotatable mandrel, an abutment mounted thereon for axial movement, a plurality of restraining devices to oppose the axial movement of said abutment, and wire delivery means to deliver a wire to said mandrel to be coiled thereon against said abutment. 110

6. A wire coiling machine comprising a rotatable mandrel, a carriage adapted for relatively axial movement with relation to said mandrel and having an abutment positioned in operative relation to said mandrel, the operative face of said abutment conforming to the angular disposition of each coil with respect to the axis of the mandrel, and wire delivery means to deliver a wire to said mandrel to be coiled thereon against said abutment. 115

7. A wire coiling machine comprising a rotatable mandrel, a carriage mounted for axial movement with respect to said mandrel and having an abutment positioned in operative coiling relation to said mandrel, said abutment having a spire receiving and forming face substantially normal to the axis of 125

the mandrel, and wire delivery means to deliver a wire to said mandrel, substantially in the plane of the spire receiving face of the abutment, whereby the same may be coiled against said abutment and the carriage may be moved axially of said mandrel.

8. A wire coiling machine comprising a rotatable mandrel, an abutment encircling the same and mounted for relatively axial 10 movement with respect thereto, and having an abutment receiving face conforming in outline to the coils of the wire, and wire delivery means to deliver wire to said mandrel to be coiled thereon against said abutment.

15. 9. A wire coiling machine comprising a rotatable mandrel, an abutment encircling said mandrel and axially movable with respect thereto, said abutment having a face substantially normal to the axis of the mandrel, and wire delivery means to deliver wire to said mandrel to be coiled thereon against said abutment.

10. A wire coiling machine comprising a rotatable mandrel, a carriage axially movable with respect thereto and having an abutment encircling the same, and provided with a spire forming face and wire delivery means to deliver wire to said mandrel in the plane of said spire forming face to be coiled 25 thereon against said abutment.

11. A wire coiling machine comprising a rotatable mandrel, means for delivering thereto a wire having an elongated dimension in cross section, and coöperating coiling 35 means to coil said wire upon the mandrel with the elongated cross dimension thereof at right angles to the axis of the coil, said coiling means being movable axially of the abutment and friction restraining means to 40 oppose such movement of the abutment.

12. A wire coiling machine comprising a rotatable mandrel, means for delivering thereto a wire having an elongated dimension in cross section and a relatively axially 45 movable wire coiling abutment disposed in wire coiling relation to said mandrel and against which said wire may be coiled on the mandrel with the elongated cross dimension thereof at right angles to the axis of the coil, 50 said abutment being moved axially of the mandrel by the wire.

13. A wire coiling machine comprising a rotatable mandrel, a relatively axially movable abutment disposed in wire coiling relation to said mandrel, and wire delivery 55 means to deliver to said mandrel wire having an elongated cross dimension, and means to position the coils of wire in a predetermined relation with respect to such elongated cross 60 dimension.

14. A wire coiling machine comprising a rotatable mandrel, wire delivery means to deliver thereto a wire having an elongated cross dimension, said delivery means permitting the delivery of the wire irrespective of 65

the disposition of the enlarged cross section thereof, means to position the wire with its elongated cross dimension at right angles to the axis of the mandrel and coöperating coiling means to coil the wire so positioned. 70

15. A wire coiling machine comprising a rotatable mandrel, wire delivery means to deliver a wire thereto to be coiled thereabout, and coöperating wire coiling means to coil the wire about the mandrel with the 75 faces of each spire or turn of the coil or helix truly normal to the axis of the mandrel.

16. A wire coiling machine comprising a rotatable mandrel, wire delivery means to deliver a wire thereto to be coiled thereabout, and a spire truing abutment in wire 80 coiling relation to said mandrel and relatively axially movable with respect thereto and against which said wire is coiled upon the mandrel. 85

17. A wire coiling machine comprising a rotatable mandrel, wire delivery means to deliver a wire thereto to be coiled thereabout, and a wire positioning and spire truing abutment in wire coiling relation to said 90 mandrel and against which the wire may be coiled upon the mandrel. 95

18. A wire coiling machine comprising a rotatable mandrel, wire delivery means to deliver a wire thereto to be coiled thereabout, and wire positioning and spire truing means in wire coiling relation to said mandrel. 95

19. A wire coiling machine comprising a rotatable mandrel, wire delivery means to 100 deliver a wire thereto to be coiled thereabout, and coöperating spire truing means effective during coiling of the wire to render the faces of each spire of the coil or helix truly normal to the axis thereof. 105

20. A wire coiling machine comprising a rotatable mandrel, an abutment and an abutment coöperative member in wire coiling relation to said mandrel and relatively axially movable with respect thereto and wire delivery means to deliver wire to said mandrel between the adjacent portions of said abutment and abutment coöperative member, the abutment and abutment coöperating member being moved axially of the mandrel by the 115 wire.

21. A wire coiling machine comprising a rotatable mandrel, an abutment and an abutment coöperative member in wire coiling relation to said mandrel and axially movable 120 with respect thereto, and wire delivery means to deliver wire to said mandrel between the adjacent portions of said abutment and abutment coöperative member, and friction means restraining the axial movement of said abutment and abutment coöperating member. 125

22. A wire coiling machine comprising a rotatable mandrel, an abutment and an abutment coöperative member encircling said 130

mandrel and axially movable with respect thereto, and wire delivery means to deliver wire to said mandrel between the adjacent portions of said abutment and abutment co-operative member.

23. A wire coiling machine comprising a rotatable mandrel, a carriage axially movable with respect thereto and carrying an abutment and an abutment co-operative member encircling said mandrel, and wire delivery means to deliver wire to said mandrel between the adjacent portions of said abutment and abutment co-operative member.

10 24. A wire coiling machine comprising a rotatable mandrel, an abutment and an abutment co-operative member in wire coiling relation with respect thereto, mounted for relatively axial movement with respect to said mandrel and provided with co-acting 15 spire truing means and means for delivering wire to said mandrel between said abutment and abutment co-operative member.

25. A wire coiling machine comprising a rotatable mandrel, an axially movable abutment and an abutment co-operative member sleeved upon said mandrel, said abutment co-operative member having an enlarged axial passage to permit axial movement of 20 said member over the coiled wire, and wire delivery means to deliver wire to said mandrel between the abutment and abutment co-operative member.

30 26. A wire coiling machine comprising a rotatable mandrel, a carriage relatively axially movable with respect to said mandrel and having mounted thereon in wire coiling relation to said mandrel an abutment and an abutment co-operative member, one of which is mounted for self-yielding movement axially of the mandrel, to accommodate itself to varying thicknesses of wire and means to deliver wire to the mandrel between the abutment and abutment co-operative member.

35 27. A wire coiling machine comprising a rotatable mandrel, a carriage axially movable with respect to said mandrel and having mounted therein and encircling said mandrel an abutment and an axially yielding abutment co-operative member, and wire delivery 40 means to deliver wire to said mandrel between the abutment and abutment co-operative member.

45 28. A wire coiling machine comprising a rotatable mandrel, a carriage axially movable with respect to said mandrel and having mounted therein and encircling said member an abutment and an axially yielding abutment co-operative member, adjusting means to vary the yielding movement of said member, and wire delivery means to deliver wire to said mandrel between said abutment and abutment co-operative member.

50 29. A wire coiling machine comprising a rotatable mandrel, an abutment and abut-

ment co-operative member sleeved upon said 65 mandrel, means for delivering wire to said mandrel between said abutment and abutment co-operative member, the adjacent faces of said abutment and abutment co-operative member being respectively concave and convex.

70 30. A wire coiling machine comprising a rotatable mandrel, a relatively axially movable abutment in wire coiling relation thereto, and having a spire forming face substantially normal to the axis of the mandrel means to deliver wire to said mandrel, and means to stop the coiling operation upon the completion of the coil.

75 31. A wire coiling machine comprising a rotatable mandrel, a relatively axially movable abutment in wire coiling relation thereto, means to deliver wire to said mandrel, and electrically controlled means to stop the machine on the completion of the coil.

80 32. A wire coiling machine comprising a rotatable mandrel, a relatively axially movable abutment in wire coiling relation thereto, means to deliver wire to said mandrel, means to stop the machine upon the completion of the coil, and means to prevent the uncoiling of the wire when the power is thrown off.

85 33. A wire coiling machine comprising a rotatable mandrel, a relatively axially movable abutment in wire coiling relation thereto, means to deliver wire to said mandrel, stopping means to stop the machine upon the completion of the coil, and means to prevent rotation of the mandrel in an opposite 90 direction.

95 34. A wire coiling machine comprising a rotatable mandrel, a relatively axially movable abutment in wire coiling relation thereto, means to deliver wire to said mandrel, and wire delivery stopping means rendered operative by the stopping of the machine.

100 35. A wire coiling machine comprising a rotatable mandrel, a relatively axially movable abutment in wire coiling relation thereto, wire delivery means, and wire delivery braking means rendered operative by the stopping of the machine.

110 36. A wire coiling machine comprising a rotatable mandrel, a relatively axially movable abutment in wire coiling relation thereto, wire delivery means, braking means therefor, mandrel rotating means and connections intermediate said braking means and mandrel rotating means to start the machine when the brake is removed.

115 37. Means to form a free wire coil comprising a rotatable mandrel forming a temporary support whereon the wire is coiled for subsequent removal and independent use, 120 an abutment in wire coiling relation to said mandrel and mounted for relatively axial movement with respect thereto, wire deliv-

ery means, mandrel rotating means, and operative connections between said wire delivery means and mandrel rotating means.

38. A wire coiling machine comprising a 5 rotatable mandrel, mandrel rotating means including a clutch, wire delivery means, braking means for the latter, and operative connections between said wire delivery and mandrel rotating means, whereby the clutch 10 may be engaged upon the disengagement of the braking means.

39. A wire coiling machine comprising a rotatable mandrel, rotating means therefor including a clutch, wire delivery means, 15 braking means therefor, and connections between said clutch and said braking means, whereby when either part is brought into machine operating position, the said other part is through said connection also brought 20 into machine operating position.

40. A wire coiling machine comprising a rotatable mandrel, an abutment in wire coiling relation thereto and mounted for relatively axial movement with respect thereto, 25 wire delivery means, and automatic and manual means to stop the rotation of the mandrel without otherwise cutting off the power from the machine.

41. A wire coiling machine comprising a 30 rotatable mandrel, an abutment in wire coiling relation thereto and mounted for relatively axial movement with respect to said mandrel, wire delivery means, braking means therefor, rotating means for said mandrel including a clutch, and electrically controlled means for stopping the machine including an armature, and connections between said braking means and said clutch whereby on the actuation of said armature 35 the braking means is applied, owing to the weight thereof and thereby acts to disengage said clutch.

42. A wire coiling machine comprising a 45 rotatable mandrel, an abutment in wire coiling relation to said mandrel and mounted for relatively axial movement with respect thereto, wire delivery means, gravity applied braking means therefor, rotating means for said mandrel including a clutch, electrical 50 connections for stopping said machine including an armature, and connections between said braking connections and said clutch, whereby upon the actuation of the armature the wire delivery means is braked 55 and the clutch disengaged.

43. A wire coiling machine comprising a 60 mandrel and means to rotate the same, a wire supporting and guiding abutment in operative wire coiling relation to said mandrel, a wire supporting and guiding abutment coöperative member also in operative wire coiling relation to said mandrel but spaced therefrom to permit the passage of the coiled wire, supporting means to sup-

port said abutment and abutment coöperative member, thereby to confine and guide between them the wire as delivered to said mandrel, means permitting the movement of said abutment and abutment coöperative member axially of the mandrel and wire 70 feeding means to deliver the wire to the mandrel between said abutment and abutment coöperative member.

44. A wire coiling machine comprising a 75 mandrel and means to rotate the same, a wire supporting and guiding abutment in operative wire coiling relation to said mandrel, a wire supporting and guiding abutment coöperative member also in operative wire coiling relation to said mandrel but 80 spaced therefrom, supporting means independent of the mandrel to support said abutment and abutment coöperative member, thereby to confine and guide between them the wire as delivered to said mandrel, 85 and wire feeding means to deliver the wire to the mandrel between said abutment and abutment coöperative member.

45. A wire coiling machine comprising a 90 mandrel and means to rotate the same, a wire supporting and guiding abutment in operative wire coiling relation to said mandrel, a wire supporting and guiding abutment coöperative member also in operative wire coiling relation to said mandrel but 95 spaced therefrom to permit the passage of the coiled wire, supporting means independent of the mandrel and relatively axially movable with respect thereto to support said abutment and abutment coöperative member, thereby to confine and guide between them the wire as delivered to said mandrel, and wire feeding means to deliver the wire to the mandrel between said abutment and abutment coöperative member. 100

46. A wire coiling machine comprising a 105 mandrel and means to rotate the same, a wire supporting and guiding abutment in operative wire coiling relation to said mandrel, a wire supporting and guiding abutment coöperative member also in operative wire coiling relation to said mandrel but 110 spaced therefrom to permit the passage of the coiled wire, a carriage supported independently of said mandrel to support said abutment and abutment coöperative member, thereby to confine and guide between them the wire as delivered to said mandrel, and wire feeding means to deliver the wire to the mandrel between said abutment and 115 abutment coöperative member.

47. A wire coiling machine comprising a 120 mandrel and means to rotate the same, a wire supporting and guiding abutment in operative wire coiling relation to said mandrel, a wire supporting and guiding abutment coöperative member also in operative wire coiling relation to said mandrel but 125

spaced therefrom to permit the passage of the coiled wire, a carriage supported independently of the mandrel and axially movable with respect thereto to support said 5 abutment and abutment co-operative member, thereby to confine and guide between them the wire as delivered to said mandrel, and wire feeding means to deliver the wire to the mandrel between said abutment and 10 abutment co-operative member.

48. A wire coiling machine comprising a mandrel and means to rotate the same, a wire supporting and guiding abutment circumferentially disposed with respect to said mandrel, a wire supporting and guiding abutment co-operative member also circumferentially disposed with respect to said mandrel but spaced therefrom to permit the passage of the coiled wire, supporting means 15 to support said abutment and abutment co-operative member, thereby to confine and guide between them the wire as delivered to said mandrel, and wire feeding means to deliver the wire to the mandrel between said 20 abutment and abutment co-operative member.

49. A wire coiling machine comprising a mandrel and means to rotate the same, a wire supporting and guiding abutment circumferentially disposed with respect to said mandrel, a wire supporting and guiding abutment coöperative member also circumferentially disposed with respect to said mandrel but spaced therefrom to permit the 30 passage of the coiled wire, supporting means independent of the mandrel to support said abutment and abutment coöperative member, thereby to confine and guide between them the wire as delivered to said mandrel, and 35 wire feeding means to deliver the wire to the mandrel between said abutment and abutment coöperative member.

50. A wire coiling machine comprising a mandrel and means to rotate the same, a wire supporting and guiding abutment circumferentially disposed with respect to said mandrel, a wire supporting and guiding abutment coöperative member also circumferentially disposed with respect to said mandrel but spaced therefrom to permit the passage of the coiled wire, supporting means independent of the mandrel and relatively axially movable with respect thereto to support said abutment and abutment coöperative member, thereby to confine and guide between them the wire as delivered to said mandrel, and wire feeding means to deliver the wire to the mandrel between said abutment and abutment coöperative member.

60 51. A wire coiling machine comprising a mandrel and means to rotate the same, a wire supporting and guiding abutment circumferentially disposed with respect to said mandrel, a wire supporting and guiding

abutment coöperative member also circumferentially disposed with respect to said mandrel but spaced therefrom to permit the passage of the coiled wire, a carriage supported independently of said mandrel to support said abutment and abutment coöperative member, thereby to confine and guide between them the wire as delivered to said mandrel, and wire feeding means to deliver the wire to the mandrel between said abutment and abutment co- operative member.

52. A wire coiling machine comprising a mandrel and means to rotate the same, a wire supporting and guiding abutment circumferentially disposed with respect to said mandrel, a wire supporting and guiding abutment coöperative member also circumferentially disposed with respect to said mandrel but spaced therefrom to permit the passage of the coiled wire, a carriage supported independently of the mandrel and axially movable with respect thereto to support said abutment and abutment coöperative member, thereby to confine and guide between them the wire as delivered to said mandrel, and wire feeding means to deliver the wire to the mandrel between said abutment and abutment coöperative member. 80 85 90

53. A wire coiling machine comprising a mandrel and means to rotate the same, a wire supporting and guiding abutment in operative wire coiling relation to said mandrel, a wire supporting and guiding abutment co-operative member also, in operative wire coiling relation to said mandrel but spaced therefrom to permit the passage of the coiled wire, supporting means independent of said mandrel and relatively axially movable with respect thereto to support said abutment and abutment co-operative member, thereby to confine and guide between them the wire as delivered to the mandrel, wire delivery means to feed the wire to the mandrel between said abutment and abutment co-operative member, and wire delivery stopping means operative upon the stopping of the machine.

54. A wire coiling machine comprising a mandrel and means to rotate the same, a wire supporting and guiding abutment in operative wire coiling relation to said mandrel, a wire supporting and guiding abutment co-operative member also in operative wire coiling relation to said mandrel but spaced therefrom to permit the passage of the coiled wire, supporting means independent of the mandrel and relatively axially movable with respect thereto to support said abutment and abutment co-operative member, thereby to confine and guide between them the wire as delivered to the mandrel, wire delivery means to feed the wire to the mandrel between said abutment and abutment co- 120
operative member, and a wire coiling 125
relation between the wire supporting and guiding abutment and the wire supporting and guiding abutment co-operative member.

operative member, and wire delivery braking means operative upon the stopping of the machine.

55. A wire coiling machine comprising a mandrel and means to rotate the same, a wire supporting and guiding abutment in operative wire coiling relation to said mandrel, a wire supporting and guiding abutment coöperative member also in operative wire coiling relation to said mandrel but spaced therefrom to permit the passage of the coiled wire, supporting means independent of the mandrel and relatively axially movable with respect thereto to support said abutment and abutment coöperative member, thereby to confine and guide between them the wire as delivered to the mandrel, wire delivery means to feed the wire to the mandrel between said abutment and abutment coöperative member, braking means for said wire delivery means and connections between said braking means and mandrel rotating means to start the machine when the brake is removed.

25 56. A wire coiling machine comprising a mandrel and means to rotate the same, a wire supporting and guiding abutment in operative wire coiling relation to said mandrel, a wire supporting and guiding abutment coöperative member also in operative wire coiling relation to said mandrel but spaced therefrom to permit the passage of the coiled wire, supporting means independent of the mandrel and relatively axially movable with respect thereto to support said abutment and abutment coöperative member, thereby to confine and guide between them the wire as delivered to the mandrel, wire delivery means to feed the wire to the mandrel between said abutment and abutment coöperative member, and operative connections between said wire delivery means and said mandrel rotating means.

57. A wire coiling machine comprising a mandrel and means to rotate the same including a clutch, a wire supporting and guiding abutment in operative wire coiling relation to said mandrel, a wire supporting and guiding abutment coöperative member also in operative wire coiling relation to said mandrel but spaced therefrom to permit the passage of the coiled wire, supporting means independent of the mandrel and relatively axially movable with respect thereto to support said abutment and abutment coöperative member, thereby to confine and guide between them the wire as delivered to the mandrel, wire delivery means to feed the wire to the mandrel between said abutment and abutment coöperative member, braking means for said wire delivery means and operative connections between said wire delivery means and mandrel rotating means, whereby the clutch may be

engaged upon the disengagement of the 65 braking means.

58. A wire coiling machine comprising a mandrel and means to rotate the same including a clutch, a wire supporting and guiding abutment in operative wire coiling relation to said mandrel, a wire supporting and guiding abutment coöperative member also in operative wire coiling relation to said mandrel but spaced therefrom to permit the passage of the coiled wire, supporting means independent of the mandrel and relatively axially movable with respect thereto to support said abutment and abutment coöperative member, thereby to confine and guide between them the wire as delivered to the mandrel, wire delivery means to feed the wire to the mandrel between said abutment and abutment coöperative member, braking means for said wire delivery means and connections between said clutch and said braking means whereby when either part is brought into machine operating position, the other part is through said connection also brought into machine operating position. 90

59. A wire coiling machine comprising a mandrel and means to rotate the same, a wire supporting and guiding abutment in operative wire coiling relation to said mandrel, a wire supporting and guiding abutment coöperative member also in operative wire coiling relation to said mandrel but spaced therefrom to permit the passage of the coiled wire, supporting means independent of the mandrel and relatively axially movable with respect thereto to support said abutment and abutment coöperative member, thereby to confine and guide between them the wire as delivered to the mandrel, wire delivery means to feed the wire to the mandrel between said abutment and abutment coöperative member, and automatic and manual means to stop the machine. 100

60. A wire coiling machine comprising a mandrel and means to rotate the same, a wire supporting and guiding abutment in operative wire coiling relation to said mandrel, a wire supporting and guiding abutment coöperative member also in operative wire coiling relation to said mandrel but spaced therefrom to permit the passage of the coiled wire, means yieldingly to press said abutment coöperative member and abutment toward each other, and a carriage supported independently of the mandrel and axially movable with respect thereto to support said abutment and abutment coöperative member, thereby to confine and guide between them the wire as delivered to the mandrel, and wire delivery means to feed the wire to the mandrel between said abutment and abutment coöperative member. 120

61. A wire coiling machine comprising a

- mandrel and means to rotate the same, a wire supporting and guiding abutment in operative relation to said mandrel, a wire supporting and guiding abutment coöperative member also in operative wire coiling relation to said mandrel but spaced therefrom to permit the passage of the coiled wire, adjustable means yieldingly to press said abutment and abutment coöperative member toward each other with the desired pressure, a carriage supported independently of the mandrel and axially movable with respect thereto to support said abutment and abutment coöperative member, thereby to confine and guide between them the wire as delivered to the mandrel, and wire delivery means to feed the wire to the mandrel between said abutment and abutment coöperative member.
62. A wire coiling machine comprising a mandrel and means to rotate the same, a wire supporting and guiding abutment in operative relation to said mandrel, a wire supporting and guiding abutment coöperative member also in wire coiling relation to said mandrel but spaced therefrom to permit the passage of the coiled wire, means independent of said mandrel to support said abutment and abutment coöperative member, thereby to confine and guide between them the wire as delivered to the mandrel, wire delivery means to feed the wire to the mandrel between said abutment and abutment coöperative member, and regulable means to vary the pressure of said wire supporting and guiding abutment upon the wire.
63. A wire coiling machine comprising a mandrel and means to rotate the same, a wire supporting and guiding abutment in operative relation to said mandrel, a wire supporting and guiding abutment coöperative member also in wire coiling relation to said mandrel but spaced therefrom to permit the passage of the coiled wire, means independent of said mandrel to support said abutment and abutment coöperative member, thereby to confine and guide between them the wire as delivered to the mandrel, wire delivery means to feed the wire to the mandrel between said abutment and abutment coöperative member, and means to control the pressure of the wire supporting and guiding abutment against the wire.
64. A wire coiling machine comprising a mandrel and means to rotate the same, a wire supporting and guiding abutment in operative wire coiling relation to said mandrel, a wire supporting and guiding abutment coöperative member also in operative wire coiling relation to said mandrel but spaced therefrom to permit the passage of the coiled wire, a carriage mounted independently of the mandrel and axially movable with respect thereto to support said

abutment and abutment coöperative member, thereby to confine and guide between them the wire as delivered to the mandrel, wire delivery means to feed the wire to the mandrel between said abutment and abutment coöperative member, and regulable means whereby the pressure of said supporting and guiding abutment upon the wire may be varied.

65. A wire coiling machine comprising a mandrel and means to rotate the same, a wire supporting and guiding abutment in operative relation to said mandrel, a wire supporting and guiding abutment coöperative member also in wire coiling relation to said mandrel but spaced therefrom to permit the passage of the coiled wire, a carriage independent of said mandrel to support said abutment and abutment coöperative member, thereby to confine and guide between them the wire as delivered to the mandrel, wire delivery means to feed the wire to the mandrel between said abutment and abutment coöperative member, and carriage controlling means to control the pressure of said wire supporting and guiding abutment against the wire.

66. A wire coiling machine comprising a mandrel and means to rotate the same, a carriage supported independently of the mandrel for relative axial movement with respect thereto, a wire supporting and guiding abutment mounted in said carriage and in operative wire coiling relation to said mandrel, a wire supporting and guiding abutment coöperative member also mounted in said carriage in operative relation to said mandrel but spaced therefrom to permit the passage of the coiled wire, said abutment and abutment coöperative member being independently removable from said carriage.

67. A wire coiling machine comprising a mandrel and means to rotate the same, a carriage supported independently of the mandrel for relative axial movement with respect thereto, a wire supporting and guiding abutment mounted in said carriage and in operative wire coiling relation to said mandrel, a wire supporting and guiding abutment coöperative member also mounted in said carriage in operative relation to said mandrel but spaced therefrom to permit the passage of the coiled wire, said abutment and abutment coöperative member being independently removable from said carriage and means yieldingly to press the same toward each other.

68. A wire coiling machine comprising a mandrel and means to rotate the same, a carriage mounted independently of said mandrel and axially movable with respect thereto, a wire supporting and guiding abutment mounted in said carriage in operative wire coiling relation to said mandrel, a wire supporting and guiding abutment co-

- operative member also in wire coiling relation to said mandrel but spaced therefrom to permit the passage of the coiled wire, adjustable means yieldingly to press said abutment and abutment coöperative member toward each other, said abutment coöperative member being mounted in the carriage for removal therefrom without disturbing said adjustment.
69. A wire coiling machine comprising a mandrel and means to rotate the same, a carriage mounted independently of said mandrel and relatively axially movable with respect thereto, a wire supporting and guiding abutment in operative wire coiling relation to said mandrel and fixedly supported in said carriage, a wire supporting and guiding abutment coöperative member slidingly mounted in said carriage in wire coiling relation to said mandrel but spaced therefrom to permit the passage of the coiled wire, spring controlled means to force said abutment coöperative member toward said abutment and means to vary the tension of said spring.
70. A wire coiling machine comprising a mandrel and means to rotate the same, a carriage mounted independently of said mandrel and relatively axially movable with respect thereto, a wire supporting and guiding abutment in operative wire coiling relation to said mandrel and fixedly supported in said carriage, a wire supporting and guiding abutment coöperative member slidingly mounted in said carriage in wire coiling relation to said mandrel but spaced therefrom to permit the passage of the coiled wire, limiting means engaging said abutment coöperative member to limit the sliding movement thereof from said abutment and spring controlled supporting means for said limiting means.
71. A wire coiling machine comprising a mandrel and means to rotate the same, a carriage mounted independently of said mandrel and relatively axially movable with respect thereto, a wire supporting and guiding abutment in operative wire coiling relation to said mandrel and fixedly supported in said carriage, a wire supporting and guiding abutment coöperative member slidingly mounted in said carriage in wire coiling relation to said mandrel but spaced therefrom to permit the passage of the coiled wire, limiting means engaging said abutment coöperative member to limit the sliding movement thereof from said abutment and adjustable spring controlled devices coöperating with said limiting means to vary the pressure of said abutment coöperative member upon the wire.
72. A wire coiling machine comprising a mandrel and means to rotate the same, a carriage mounted independently of said mandrel and relatively axially movable with respect thereto, a wire supporting and guiding abutment mounted in said carriage and in operative wire coiling relation to said mandrel, a wire supporting and guiding abutment coöperative member slidingly mounted in said carriage and in operative wire coiling relation to the mandrel but spaced therefrom to permit the passage of the coiled wire, means engaging said sliding abutment coöperative member to limit the extent of sliding movement thereof, and provisions to permit disengagement of said limiting means and said abutment coöperative member to permit removal of the latter from the carriage.
73. A wire coiling machine comprising a mandrel and means to rotate the same, a carriage mounted independently of said mandrel and relatively axially movable with respect thereto, a wire supporting and guiding abutment mounted in said carriage and in operative wire coiling relation to said mandrel, a wire supporting and guiding abutment coöperative member slidingly mounted in said carriage and in operative wire coiling relation to the mandrel but spaced therefrom to permit the passage of the coiled wire, means engaging said sliding abutment coöperative member to limit the sliding movement thereof, spring controlled means maintaining said limiting means in position and provisions to permit the disengagement of said limiting means and said sliding abutment coöperative member to permit the withdrawal of the latter from the carriage.
74. A wire coiling machine comprising a mandrel and means to rotate the same, a carriage mounted independently of said mandrel and relatively axially movable with respect thereto, a wire supporting and guiding abutment mounted in said carriage and in operative wire coiling relation to said mandrel, a wire supporting and guiding abutment coöperative member slidingly mounted in said carriage and in operative wire coiling relation to the mandrel but spaced therefrom to permit the passage of the coiled wire, means engaging said sliding abutment coöperative member to limit the sliding movement thereof, adjustable spring controlled means to maintain said limiting means in position and provisions to disengage said limiting means from said sliding abutment member without disturbing the said adjustment, thereby to permit the withdrawal of said sliding abutment coöperative member from said carriage.
75. A wire coiling machine comprising a mandrel, means to support the same, means including a ball and ratchet clutch to prevent reverse rotation of said mandrel, a wire supporting and guiding abutment in operative wire coiling relation to said mandrel, a wire supporting and guiding abutment co-

operative member also in operative wire coiling relation to said mandrel but spaced therefrom to permit the passage of the coiled wire, and a carriage mounted independently of said mandrel and relatively axially movable with respect thereto, wherein said abutment and abutment coöperative member are mounted to confine and guide between them the wire as delivered to the mandrel between said abutment and abutment coöperative member.

76. A wire coiling machine comprising a mandrel and means to rotate the same, a wire supporting and guiding abutment in operative wire coiling relation to said mandrel, a wire supporting and guiding abutment coöperative member also in operative wire coiling relation to said mandrel but spaced therefrom to permit the passage of the coiled wire, means supported independently of said mandrel to support said abutment and abutment coöperative member, thereby to confine and guide between them the wire as delivered to said mandrel, and wire feeding means to deliver the wire to the mandrel between said abutment and abutment coöperative member.

77. A wire coiling machine comprising a rotatable mandrel, an abutment mounted thereon for relatively axial movement, the operative face of the abutment conforming to the angular disposition of each coil with respect to the axis of the mandrel, and wire delivery means to deliver a wire to said mandrel to be coiled thereon against said abutment.

78. A wire coiling machine comprising a rotatable mandrel, wire delivery means to deliver thereto a wire having an elongated cross dimension, said delivery means permitting the delivery of the wire irrespective of the disposition of the enlarged cross dimension thereof, and means to position the wire with its elongated cross dimension at a predetermined angle to the axis of the mandrel as the wire is coiled thereon.

79. A wire coiling machine comprising a rotatable mandrel, a carriage relatively axially movable with respect to said mandrel and having mounted thereon in wire coiling relation to said mandrel an abutment and an abutment coöperative member, one of which is mounted for self-yielding movement axially of the mandrel to accommodate itself to varying thicknesses of wire, said mechanism having provisions permitting the delivery of wire to the mandrel.

80. A wire coiling machine comprising a rotatable mandrel, a carriage axially movable with respect to said mandrel and having mounted thereon and encircling said mandrel an abutment and an abutment coöperative member, said abutment and abutment coöperative member being relatively yield-

ing axially of the mandrel and wire delivery means to deliver wire to said mandrel between the abutment and abutment coöperative member.

81. A wire coiling machine comprising a rotating mandrel, a relatively axially movable abutment in wire coiling relation thereto, means to deliver wire to said mandrel and an electric circuit including an armature adapted to be actuated upon the completion of a predetermined length of coil thereby to stop the machine.

82. A wire coiling machine comprising a rotatable mandrel, an abutment in wire coiling relation to said mandrel and mounted for relatively axial movement with respect thereto, wire delivery means fixed with respect to the mandrel, mandrel rotating means and operative connections between said wire delivery and mandrel rotating means.

83. A wire coiling machine comprising a rotatable mandrel, an abutment in wire coiling relation thereto and mounted for relatively axial movement with respect to said mandrel, wire delivery means, braking means therefor, rotating means for said mandrel including a clutch, and electrically controlled means for stopping the machine including an armature, and connections between said braking means and said clutch whereby on the actuation of said armature the braking means is applied and acts to disengage said clutch.

84. A wire coiling machine comprising a mandrel and means to rotate the same, a carriage supported independently of the mandrel for relative axial movement with respect thereto, a wire supporting and guiding abutment mounted in said carriage and in operative wire coiling relation to said mandrel, a wire supporting and guiding abutment coöperative member also mounted in said carriage in operative relation to said mandrel but spaced therefrom to permit the passage of the coiled wire, said abutment and abutment coöperative member being removable from said carriage, and means yieldingly to press the same toward each other.

85. A wire coiling machine comprising a rotatable mandrel, mandrel rotating means including a clutch, wire delivery means and operative connections between the wire delivery means and the mandrel rotating means, whereby the wire delivery means is rendered inoperative upon the disengagement of the clutch.

86. A wire coiling machine comprising a rotatable mandrel, mandrel rotating means including a clutch, means to disengage the clutch upon the completion of a predetermined length of coil, and operative connections between the wire delivery means and

the mandrel rotating means, whereby the wire delivery means is rendered inoperative upon the disengagement of the clutch.

87. A wire coiling machine comprising a 5 rotatable mandrel, rotating means therefor, including means to stop the rotation of the mandrel upon the completion of a coil of predetermined length, wire delivery means, and operative connections between the mandrel rotating means and the wire delivery means whereby the wire delivery means is rendered inoperative when the means to stop the rotation of the mandrel is rendered effective.

15 88. A wire coiling machine comprising a rotatable mandrel, rotating means therefor, including means to stop the rotation of the mandrel upon the completion of a coil of predetermined length, an abutment against 20 which the wire is coiled, said abutment and mandrel being relatively movable axially of the mandrel, wire delivery means, and operative connections between the mandrel rotating means and the wire delivery means, 25 whereby the wire delivery means is rendered inoperative when the means to stop the rotation of the mandrel is rendered effective.

89. A wire coiling machine comprising a rotatable mandrel, rotating means therefor, 30 including means to stop the rotation of the mandrel upon the completion of a coil of predetermined length, an abutment upon the mandrel movable axially thereof, the wire being coiled against said abutment, 35 wire delivery means and operative connections between the mandrel rotating means and the wire delivery means, whereby the wire delivery means is rendered inoperative when the means to stop the rotation of the 40 mandrel is rendered effective.

90. A wire coiling machine comprising a rotatable mandrel, mandrel rotating means including means to stop the rotation of the mandrel upon the completion of a predetermined length of coil, wire delivery means, 45 braking means for the latter, and operative connections between the wire delivery means and mandrel rotating means whereby the means to stop the rotation of the mandrel 50 is rendered ineffective upon the disengagement of the braking means.

91. A wire coiling machine comprising a rotatable mandrel, rotating means therefor including means to stop the rotation thereof, 55 wire delivery means, braking means therefor and connections between said mandrel rotation stopping means and said braking means, whereby when either part is brought into machine operating position the 60 said other part is through said connection also brought into machine operating position.

92. A wire coiling machine comprising a plurality of rotatable mandrels, abutments

in wire coiling relation to each mandrel and 65 mounted for relative axial movement with respect thereto, and means to stop the rotation of any one of the mandrels upon the completion of a predetermined length of coil without stopping the rotation of the other 70 mandrels.

93. A wire coiling machine comprising a plurality of rotatable mandrels, abutments 75 in wire coiling relation to each mandrel and mounted for relative axial movement with respect thereto, and automatic means to stop the rotation of any one of the mandrels upon the completion of a predetermined length of coil without stopping the rotation of the other mandrels. 80

94. A wire coiling machine comprising a plurality of rotatable mandrels, abutments in wire coiling relation to each mandrel and mounted for relative axial movement with respect thereto, and automatic and manual 85 means to stop the rotation of any one of the mandrels upon the completion of a predetermined length of coil without stopping the rotation of the other mandrels.

95. A wire coiling machine comprising a 90 rotatable mandrel, an abutment, an abutment coöperating member sleeved upon said mandrel, and means for delivering wire to said mandrel between said abutment and abutment coöperative member, the adjacent 95 faces of said abutment and abutment coöperative member being formed to true the spires of the coiling wire.

96. A wire coiling machine comprising a rotatable mandrel, a relatively axially movable abutment in wire coiling relation thereto, an abutment coöperative member opposed to said abutment, means to deliver wire to said mandrel, stopping means to stop the machine upon the completion of the 100 coil, and means to prevent rotation of the 105 mandrel in an opposite direction.

97. A wire coiling machine comprising a rotatable mandrel, a relatively axially movable abutment in wire coiling relation thereto, an abutment coöperative member opposed to said abutment, means to deliver wire to said mandrel, and wire delivery stopping means rendered operative by the stopping 110 of the machine.

98. A wire coiling machine comprising a rotatable mandrel, a relatively axially movable abutment in wire coiling relation thereto, an abutment coöperating member opposed to said abutment, wire delivery means, and 120 wire delivery braking means rendered operative by the stopping of the machine. 115

99. Means to form a free wire coil comprising a rotatable mandrel forming a temporary support whereon the wire is coiled 125 for subsequent removal, an abutment in wire coiling relation to said mandrel and mounted for relative axial movement with respect

thereto, an abutment coöperative member, wire delivery means, mandrel coöperating means, wire rotating means, and operative connections between said wire delivery and mandrel coöperating means, said abutment and abutment coöperative member being formed with spire truing faces.

100. A wire coiling machine comprising a rotatable mandrel, an abutment, an abutment coöperative member sleeved upon said mandrel, means for delivering wire to said mandrel between said abutment and abutment coöperative member, the adjacent faces of the abutment and abutment coöperative member being substantially normal to the axis of the mandrel but formed to true the spires of the coiling wire.

101. A wire coiling machine comprising a mandrel, an abutment, an abutment coöperative member extending circumferentially of said mandrel and between which and said abutment wire may be supplied to be coiled, the adjacent faces of the abutment and abutment coöperative member being formed to true the spires of the coiling wire.

102. A wire coiling machine comprising in combination a mandrel, an abutment coöperative member extending circumferentially of said mandrel and between which and said abutment wire may be introduced to be coiled, the adjacent faces of the abutment and abutment coöperative member being slightly concave and convex respectively.

103. A wire coiling machine comprising in combination a mandrel and coöperating abutment members positioned in operative relation to said mandrel to receive the wire between them, the adjacent faces of said members being out of a plane cutting the mandrel normal to the axis thereof to true the spires of the coiling wire.

104. A wire coiling machine comprising in combination a wire supporting and coil-

ing member, and coöperating abutment members positioned in operative relation to said supporting and coiling member to receive the wire between them, the adjacent faces of said coöperating abutment members being curved to true the spires of the coiling wire.

105. A wire coiling machine comprising in combination a wire coiling member and coöperating means having a surface slightly deflected from parallelism with the spires of the completed wire, thereby to true the spires of the coiling wire.

106. A wire coiling machine comprising in combination a wire coiling member and coöperating means active upon the completely coiled wire and having two substantially parallel surfaces slightly deflected from parallelism with the spires of the completed wire, thereby to true the spires thereof.

107. A wire coiling machine comprising, in combination, a wire coiling member and coöperating means active upon the completely coiled wire and having two substantially parallel surfaces deflected from parallelism with the spires of the completed wire to true the spires thereof.

108. A wire coiling machine comprising in combination, a wire supporting and coiling member, and coöperating abutment members positioned in operative relation to said supporting and coiling member to receive the wire between them, the adjacent faces of said coöperating abutment members being eccentric to a plane cutting the mandrel normal to the axis thereof.

In testimony whereof I have signed my name to this specification in the presence of two subscribing witnesses.

EDGAR F. HATHAWAY.

THOMAS B. BOOTH.

Copies of this patent may be obtained for five cents each, by addressing the "Commissioner of Patents
Washington, D. C."

It is hereby certified that in Letters Patent No. 1,207,911, granted December 12, 1916, upon the application of Edgar F. Hathaway, of Boston, Massachusetts, for an improvement in "Wire-Coiling Machines," an error appears in the printed specification requiring correction as follows: Page 11, line 86, claim 73, for the word "amutment" read *abutment*; and that the said Letters Patent should be read with this correction therein that the same may conform to the record of the case in the Patent Office.

Signed and sealed this 30th day of January, A. D., 1917.

[SEAL.]

F. W. H. CLAY,
Acting Commissioner of Patents.

Cl. 153—64.
